METHOD OF AND RADIANT HEAT STILLS
FOR DISTILLING HYDROCARBON OILSDonald L. Thomas, New York, N. Y., assignor, by
mesne assignments, to Gasoline Products Com-
pany, Inc., Newark, N. J., a corporation of
Delaware

Application November 21, 1931, Serial No. 576,518

16 Claims. (Cl. 196—116)

This invention relates to improvements in oil stills, particularly of oil cracking stills of the radiant heat type, and involves an improved method of arranging and distributing the heating surfaces of such stills whereby danger of overheating the oil is avoided, and a more uniform heating action is obtained with lower heating surface requirements.

The tendency in conventional tubular heater design has been the application of both radiant and convection heat transfer in a furnace, with two distinct heating zones. The first section of such a furnace consisted of tubes in view of the flame absorbing heat by radiation, while the secondary bank shielded from the flame, absorbed heat by convection from the somewhat cooled flue gases flowing over the tubes. To insure mild furnace conditions and to protect the tubes nearest the flame, excess air ranging from fifty per cent to one hundred per cent of that necessary for combustion has been employed. As a further effort to obtain mild heating conditions in some cracking furnaces where the oil is heated to temperatures of 900° F. or more, the flue gases have been recirculated in order to cool the products of combustion and relieve the tubes nearest the fire of too great a burden.

Flue gas recirculation is indeed an effective control particularly on cracking furnaces of the two-zone type, in that the distribution of heat pickup between the two banks, may readily be varied by an increase or decrease in percentage of gases returned to the combustion zone.

However, in such furnaces the rate of heat transfer may be as high as 12,000 B. t. u. per square foot per hour in the tubes near the flame, while in the cooler portion of the convection bank the rate may be as low as 1000 B. t. u. per square foot per hour. Also in such furnaces from fifty per cent to sixty per cent of the total heat absorbed by the oil is picked up in the radiant section.

Recent developments have shown that a much greater portion of the total heat absorbed by the oil can be transferred by radiation with the same overall efficiency, but with much less surface. Experiments on existing two-zone furnaces clearly indicate that, where formerly fifty to sixty per cent of the total heat absorbed by the oil was radiant energy, now eighty per cent or more of the heat picked up may be radiant energy. Tubular heaters are now being designed of the two-zone box type, with more than four-fifths of the heat absorbed by the oil in tubes in view of the flame.

The usual designs of heat absorbing surfaces of conventional furnaces are often accompanied by inconsistency between the volume and the surface of furnace since the achievement of complete combustion independently determines the volume of the furnace according to its rate of heat liberation, thus determining the furnace dimensions. The surface of furnace walls thus obtained often presents an insufficient area for the distribution of the absorbing surfaces, necessary for reducing the gas temperatures to a desirable degree. Yet, the usual gas velocities in the first rows of tubes render the coefficients of heat transmission through convection comparatively small. The question arises as to the most adequate temperature at which the heat transmission through convection should be preferred to that taking place through radiation.

The drop in the gas temperature reduces the intensity of the heat transferred through radiation so that at a certain temperature, the limit is reached when it becomes profitable to adopt the transmission of heat through convection. Calculations show, this limit usually fluctuates between 1,400° F. and 1,800° F. i. e. theoretically it appears profitable to cool gases in the furnace down to 1,400° F. to 1,800° F. and after that only let them enter the nest of tubes in the convection bank where the heat transmission through convection will take place.

It is manifest that such a drop in temperature at the end of the furnace cannot affect the completeness of combustion unless the combustion chamber is incorrectly designed. Certain temperatures are required for the completeness of combustion at those points only where the combustion as such takes place; as soon as combustion is complete it becomes the object of the designer to attain maximum intensity of gas cooling by whatever means he may choose.

Pursuing the above process of reasoning I may state that, from the standpoint of minimum use of heating surfaces, the most expedient principle consists in maintaining sufficiently high temperatures in the initial portions of the flame in which the combustion takes place and, on the other hand, very intense cooling furnace temperatures down to 1,400° to 1,800° F. through radiation by the end of the flame where the combustion is already complete. However, for such intense cooling, the surface of the furnace wall is usually insufficient to comprise the requisite heat-absorbing area, especially when turbulent atomizers are provided as well as other arrangements se-

curing such increase of rates of heat liberation per unit furnace volume as to reduce both the volume and the surface of the furnace.

In order to obviate these difficulties, as well as to give the designer full liberty in distributing the requisite ray absorbing surfaces, I have elaborated a novel principle of furnace cooling as applied to oil stills which is illustrated in the accompanying drawings, wherein

10 Figure 1 is a vertical cross-section of a tube still embodying in its design the principles set forth above;

Fig. 2 is a vertical longitudinal section of the still shown in Fig. 1, the view being taken along 15 the line A—A of Fig. 1;

Fig. 3 is a vertical cross-section of a modified type of still which utilizes the same principles;

Fig. 4 is an outside elevation of these types of 20 still. This figure corresponds to Fig. 2, being an outside view thereof, showing the buckstays and tube supports used with this kind of still;

Fig. 5 is a vertical cross-sectional view of a type 25 of steam controller for the steam turbines employed in driving the centrifugal pumps which feed oil to these stills;

Fig. 6 is a type of protective sheath shown on 30 a tube which may be used in connection with the radiant heat tubes of these stills to protect them from any tendency to overheating, should it develop;

Fig. 7 is a cross-section of a still tube with one of these sheaths in place thereon;

Fig. 8 is a cross-section of a still tube similar 35 to Fig. 7, except that two sheaths, one over the other, are employed;

Figs. 9, 10, 11 represent tube supports for these still tubes in the free space of the still, the supports being attached to steel beams that usually 40 support the refractory blocks constituting the roof of the furnace;

Fig. 12 is a vertical cross-section of a portion 45 of the still wall, say on the line B—B of Fig. 4, and is designed to show how the ends of the roof tubes where they pass through the side wall, are supported;

Fig. 13 is an enlarged cross-section of some of the supporting members shown in Fig. 12;

Fig. 14 is a transverse cross-section of the top 50 horizontal buckstay support for the roof tubes, as shown in Figs. 4 and 12;

Fig. 15 is a polar diagram illustrating the radiant heat absorption of one row of still tubes located near a wall surface and receiving heat 55 from one side;

Fig. 16 is a polar diagram illustrating the radiant heat absorption of one row of still tubes supported in free space and receiving heat from both sides;

60 Fig. 17 is a vertical longitudinal cross-section of a horizontal tube two-zone box type radiant heat still designed according to this invention, and having in addition a digestion coil in the roof thereof;

65 Fig. 18 is a horizontal cross-section of a modified form of vertical tube radiant heat still, (De Florez type) designed according to the principles of this invention and having in addition a digestion coil adjacent the still walls.

70 As may be seen from Fig. 2 the usual roof tubes 3 have depending portions 3¹ to 3¹² extending downward to a distance equivalent to about 1/8 to 1/2 the furnace height, the depending rows being placed wide apart. An average distance apart 75 of 20 to 24 inches between the ribbed surfaces so

formed, is usually sufficient, as such intervals yield sufficiently thick gas layers possessed of intense radiation. Due to the fact that gas layers of 20 inches thickness are capable of absorbing at least 92 percent of the total radiant heat falling on them, such layers, by reradiating this absorbed heat act as secondary radiant heat sources for the ribbed tube surfaces presented by the rows. Moreover, the tube surfaces of these well spaced sections operate two-sidedly as they 10 receive heat from both sides, and where the ribbed surfaces consist of a single row of depending tubes as in Fig. 17, each single tube receives heat from both sides, in contra-distinction to the double tube rows in Fig. 2 where each tube 15 receives heat mainly from one side, although a partial transmission of heat rays occurs between the spaced tubes of the opposite row. In this latter case, however, the heat transmission from the back averages only about 1/4 of that received 20 by the front tube surface. With single rows, calculations show that such spaced tube sections form much more efficient heat absorbers than the first rows of tubes adjacent a furnace wall as employed in the usual type of radiant heat still. 25 The polar diagrams of Figs. 15 and 16, bring out clearly the advantages of the double exposed single row of tubes over the double row, as used in Fig. 2.

A similar principle of construction of ray absorbing surfaces may also be applied to cylindrical vertical placed tube stills of the De Florez type, (see Fig. 18). In this case, it also is expedient to space the nest of tubes of the first row 30 so that only separate rows of tubes remain located on the inner arcs of the furnace center. 35

In its actual idea the new principle of ray absorption means the use of ribbed surfaces, though the ribs should not form continuous plates, but rows of tubes of which the fundamental plane of the axes of the tubes is perpendicular either to the fundamental surface of the furnace wall, or to the plane of the first row or rows of wall tubes.

Referring to Figs. 1 and 2, 1 is the combustion chamber of a tube still of the two-zone box type, 2 and 2¹ are the burners therefor, arranged for gas, pulverized coal or oil firing, as desired; 3 to 3¹² are the tube banks forming the radiant heat section of the still, 4 is the convection bank 50 forming the economizer section which in this still is of comparatively small dimensions as its main function is simply that of a heat balancing coil to aid in controlling the still temperatures of the oil being treated; it may for 55 instance be 5 rows wide and 10 tube rows high and is designed to pick up from 10 to 20 percent of the total heat to be transferred. The heat remaining in the flue gases after passing this coil is recovered in an air heater 5, located beneath the coil, the flue gases passing the air heater escaping by the opening 6, to the customary underground flue leading to the tube stack.

Most stills of the type illustrated employ only a single series oil circuit, but in the still illustrated a two-circuit series type is shown, that is to say, there are two separate and distinct series of connected oil circuits extending throughout the furnace heating space, which circuits are fed with charging stock by means 65 of a steam driven centrifugal pump.

Referring to Fig. 2, the centrifugal pump 9 which in this instance consists of two separate centrifugal pumps placed end to end on the same drive shaft, so as to be driven by one and the 75

same motor. These pumps have their discharges located at the near center and adjacent to each other, which arrangement does away with the necessity for shaft stuffing boxes at this point 5 as the oil pressures in the two circuits is the same throughout. This is a very important point in a pump intended to handle hot oils, as this one is, and avoids much complication. As the inlets are under more or less internal suction, shaft packing difficulties do not present themselves at this point. 9^1 is the inlet to the pumps and is branched into two mains 9^2 , 9^3 leading to the pump inlets as shown. The pump outlets connect to mains 9^4 , 9^5 which deliver the 10 charging stock for each coil to the coil inlets 4^3 , 4^4 (Figs. 1 and 2) of the convection bank of tubes 4 , the tubes, forming the two circuits, of which are connected together as indicated by the chained lined tube circuits of Fig. 1. After 15 passing through the convection bank the oil leaves by way of the transfer lines 4^1 and 4^2 of Figs. 1 and 2 each leading to a radiant heat circuit, of the type described above, located in the upper part of the combustion chamber.

20 These radiant heat circuits, as previously explained, are made up of a series of ribbed surfaces consisting of downwardly depending rows of horizontally disposed tubes, the rows spaced from one another a distance of from 20 to 24 inches. The latter distance is preferred for general use. It is to be clearly understood that while the tube rows may extend downward nearly to one-half the furnace height, nevertheless the furnace dimensions and the positions of the 25 burners in reference thereto are to be so correlated to one another that combustion of all fuel is to be entirely completed before any part of the combustion gases contact with these tubes. This, of course, implies the use of comparatively 30 large furnace volumes, although the fact remains that a furnace with this type of cooling surface operates with little or no excess air and tends to small volumetric capacity as practically all of the heat absorbing surface is of the radiant heat type and works at high ratings.

In the furnace design shown in Fig. 2, the tubes making up the ribbed surface are in the form of double rows. It is however, preferable wherever possible to employ single rows of tubes 35 as indicated in Figs. 4 and 17, as this permits of full two-sided application of radiant heat from the gases, to both sides of the tubes of each row which, as pointed out above, is of special advantage.

40 There are, as stated, two radiant heat circuits, one consisting of tube rows from 3^1 to 3^6 inclusive, which is connected to transfer line 4^1 . The other radiant heat circuit is made up of tube rows from 3^7 to 3^{12} inclusive, and connects 45 to the other transfer line 4^2 . The oil after passing through these circuits escapes by the flanged outlets 10 and 11 leading from the still.

The centrifugal pump 9 that delivers charging stock to the still is usually driven by a steam turbine 7 . A notable feature in connection with this turbine is the manner of controlling its speed. As the rotary speed of the turbine governs the delivery pressures of the centrifugal pumps, it is self-evident that where we want to 50 alter this delivery pressure, it will be necessary to alter the turbine speed.

In order to do this and at the same time keep the turbine speed steady, there is provided a pressure actuated controller 8 , which controls 55 the steam flow in correspondence with the pres-

sure differential existing between the pump outlets, which corresponds to the inlet pressure of the tube still and the outlet pressure of said still, existing at the outlet openings 10 and 11 of Fig. 2.

5 A detailed view of this controller is given in Fig. 5 from which it can be seen that it consists of a double seated balanced poppet steam throttle valve 8^9 located in the casing 8 . The valve rod 8^{12} is connected at top and bottom to two similar sized expandable type metallic bellows 8^5 and 8^6 . The top of the valve rod 8^9 is connected to one end of the metallic bellows 8^5 , this end being hermetically sealed against entrance of steam into the bellows interior. The other end of the bellows is also hermetically sealed to the upper chamber wall of the casing 8 , as shown. Thus while the valve rod is movably supported by the bellows, yet no steam can directly enter the bellows interior. However an opening to said interior is provided by the pipe connection 8^{10} . A similar arrangement is provided in connection with bellows 8^6 to which the lower end of the valve rod is attached as shown, and which has an inlet 8^{11} as above specified. In addition to the above, the lower portion of the valve rod carries a spring 8^7 , one end of which bears against the upper end of bellows 8^6 tending to collapse it. The other end of the spring bears against a movable member 8^{13} carried by a rotatable threaded rod 8^8 by which the tension of spring 8^7 can be altered as desired. 8^1 is the steam inlet to the controller and 8^2 is the steam outlet leading to the turbine.

35 The controller is connected to the turbine and to the oil circuits of the still about as diagrammatically indicated in Fig. 2. From this it will be seen that the bellows inlet pipe 8^{10} is connected to the inlet mains leading to the still, a small bore pipe 9^6 connected to each main and to the controller conduit being used for this purpose. In a similar manner the pipe 8^{11} of bellows 8^6 is connected to each of the outlets 10 and 11 of the still proper. As both bellows have the same 40 dimensions and work in opposition to each other, it is self-evident that whatever movement of the valve takes place will be due to the difference in pressure between the inlets and outlets of the still so that variations in these pressures will affect the steam flow to the turbine and thus control the pump speed in conformity therewith. However, the actual rate of steam flow due to the normal opening of the valve is controlled by 45 tension of the spring 8^7 which is adjustable by means of the threaded rod 8^8 and this adjustment, of course, controls the turbine speed and consequently the pump pressure.

50 From the above description it can be seen how oil drawn in through the inlet 9^1 of the pump and driven through the still circuits reacts on the steam controller of the turbine to regulate the speed and keep constant the pressure differential of the oil circuits at any point fixed by the operator.

55 An air preheater located below the convection bank of tubes as shown in Fig. 1, preheats the incoming air to the unusual high temperature of about 800° F. with the flue gases entering the convection bank from above at 1400° F. to 1500° F. As shown clearly in Figs. 1 and 2, this preheater consists of a two-pass box like tubular structure formed of a series of horizontal tubes in two banks separated from each other by the baffle wall 5^4 and attached to tube sheets forming 60

the inside vertical sides of the preheater casing. This steel casing which has the form shown in Figs. 1 and 2, has openings at top and bottom as shown at 5³ of Fig. 2 so that combustion gases 5 from above can pass downward therethrough over the outside of the horizontal tubes of the preheater to the still outlet 6.

In practice, air for combustion purposes is drawn in through damper controlled openings 10 12¹ in the side walls of the still shown in Fig. 1. These side openings lead into the upper part of the air space 12² in the curtain wall 12. From the upper air passage the air flows into the upper header 5¹ of the air preheater above the baffle 5⁴, 15 thence through the upper bank of tubes to the enclosed space 5⁶, having a removable door 5⁵ which space communicates with the lower bank through which the air then flows into the lower header 5¹, from which it passes into the lower air space 20 12³ of the curtain wall and thence into the air space 12⁴ of the still floor to escape finally by way of side openings 12⁵ to 12⁶ (see Fig. 2) to the burners 2, 2¹ where it is used for burning fuel in the well-known manner.

25 In the still design shown in Fig. 3, which corresponds in section to Fig. 1, there are two circuits as before stated but in this case, there are two separate economizer convection banks which are located on opposite sides of the combustion 30 chamber behind air cooled curtain walls, as shown in the figure. These economizer sections give to the still greater overall efficiency with greater flexibility and ease of control, than is obtainable with an all radiant furnace. Moreover, such a 35 bank will absorb a great deal of radiant energy from the incandescent gases above it, as well as convection heat from the stream of gas coming in contact with the tubes. Below each bank there is located an air preheater of the same 40 type and arrangement as the one already described in connection with Fig. 2.

The radiant heat section of the still is arranged similarly to the stills just described with depending tubes forming rib-like roof surfaces; 45 the tube rows which may be of either single or double formation being spaced from one another a distance corresponding to 20 to 24 inches between centers of the rows. In the free space of the still the tubes in these rows are supported at two or more points by hanger bars 13, 13¹ which extend through the roof and are attached to I-beams (not shown in this figure) that support the refractory blocks forming the still 50 roof. Types of these hangers are shown in Figs. 55 9, 10, and 11, Fig. 10 being for single row tubes, while Fig. 11 is intended for double row tubes as in Fig. 2. There are usually two extra roof tubes between the rows, as shown in Fig. 2, and Fig. 9 shows means for providing a support for these 60 extra tubes.

As the combustion chamber of this type of still usually has two flue openings 6 and 6¹ through which combustion gases are discharged to the central flue 6³, I control the flow of these 65 gases by means of dampers 6⁴ and 6⁵ in the flues, the adjustment of which permits of regulating the relative temperatures of the combustion bank economizers independently of each other.

70 As the still shown in Fig. 3 is specifically adapted for carrying out a combined cracking and distilling operation, such as described in National Petroleum News, December 4th, 1929, pages 33-39, wherein crude charging stock pre- 75 distilled before cracking by means of hot cracked

oil vapor in order to provide a clean overhead distillate as raw material for charging to the still, it is herein proposed to extend this method so as to use the hot cracked oil vapors from this still as a heat carrier to a standard type column still, 5 wherein complete distilling and fractionating of the main crude oil stock can be carried out without passing said crude oil directly through the still. In this case, the crude stock is charged direct to the column still and is distilled and fractionated therein by means of the hot cracked oil vapors from this tube still which are led into the base of the column to supply the necessary heat for the operation. Different fractions will be drawn from the side of the column still in 10 known manner and one of these fractions, usually the gas oil cut is used as the primary charging stock for the tube still. In this way the unit will operate as a combined topping, fractionating and cracking apparatus, thus avoiding the necessity of separately distilling and fractionating the crude oil. In such an operation wherein separate fractions are withdrawn from the side of the tower, it is customary to strip undesired light 15 constituents from these fractions by means of superheated steam introduced along with the fraction into a small supplementary column termed a stripper. In order to supply this superheated steam, the still shown in Fig. 3 is provided with a radiant heat type of superheater which 20 consists of a series of horizontal tubes located in recesses in the front faces of the two curtain walls which separate the convection tube banks from the combustion chamber. An inlet main 25 14 is joined to an inlet header 14² which is common to a number of horizontal tubes connected up in parallel through which the steam from main 14 passes.

The steam after passing through the tubes 30 connected to this header enters a transfer header 14⁴ in order to reach a lower set of parallel tubes wherein it again makes a reverse pass through the combustion chamber and enters header 14⁶, which is connected by way of transfer line 14⁸ to header 14⁷ which in turn serves a lower set of parallel tubes set in the face of the opposite curtain wall. After passing through these tubes 35 the steam enters transfer header 14⁵ which conveys it to the upper set of parallel tubes through 40 which it travels to reach the outlet header 14³, which in turn connects with the outlet main 14¹ leading to the strippers. From this point on the steam is handled in the customary manner and 45 needs no further description herein.

Instead of arranging the steam superheater 50 as described above, it may be constituted by a series of parallel horizontally aligned tubes in front of the bridge walls which are placed in alternate relation with a similar series of radiant 55 heat oil tubes intercalated with the steam superheater tubes and overhanging these latter in order to cool and protect these tubes from danger of overheating. This can be done by arranging the oil tubes in a plane parallel to and in advance of the superheater tubes, the alternate rows of course being placed in staggered relation to one another so that radiant heat by passing between the rows of oil tubes can readily 60 reach the superheater tubes, the latter being protected from destructive heat effects by the near presence of the oil tubes.

Fig. 4 is intended to show how the radiant heat tubes are distributed and supported in the furnace wall. This shows the outside surface of one 75

of the still walls, the view corresponding in elevation to Fig. 2, except that single vertical rows of radiant heat tubes are shown instead of double rows as in that figure.

5 Referring to Fig. 4, 15 is a heavy I-beam resting on a concrete foundation, and supports the main buckstays 16, 16¹, 16², 16³, the lower ends of which rest on the I-beam and are welded thereto. The construction of these buckstays is shown in Fig. 14, wherein it can be seen they are formed of two channeled members 16⁴, 16⁵, placed face to face and welded together as shown and to backing plates 16⁶, 16⁷. The member 17 is of similar construction and rests on top of the two-center buckstays 16¹ and 16² to which it is welded and it is also welded to the sides of the corner buckstays 16, 16³ as shown in Fig. 4. These corner buckstays, two at each corner, extend up to the roof of the still and carry on their tops connecting I-beams 18, which serve as supports for a series of smaller beams (not shown) that are used to sustain the refractory blocks which usually form the still roof. The buckstays are further connected together intermediate their tops and bottoms by means of short horizontal I-beam sections 19, 19¹, 19², which are welded to the sides of the main buckstays and serve as supports for short auxiliary buckstay sections 20, 20¹, 20², 20³, 20⁴, 20⁵, 20⁶, 20⁷, 20⁸, 20⁹, 20¹⁰, 20¹¹ connecting to the member 17 at the top and to the horizontal I-beam sections 19, 19¹, 19² at the bottom. The auxiliary buckstays serve as tube supports for the ends of the depending radiant heat tube sections, which connected together correspond to the ribbed surfaces referred to above. The openings for the radiant heat tubes are clearly shown in Fig. 4, and in the section at Fig. 14. The member 17 shown, which is similar in section to Fig. 14, supports a series of roof tubes which form part of the radiant heat circuit. The way in which the still wall is constructed and supported at this point is shown in Figs. 12 and 13. The still wall 26 is built up inside the parallelogram outlined by the buckstays so that they rest against the outside surfaces of the wall and act as supports therefor. The buckstays are bound together in parallelogram form by a series of members 18 and 15 binding their tops and bottoms together to form a single unitary box-like skeleton structure surrounding the walls.

In Fig. 12, 26 is the still wall which is carried up to the member 17 of Fig. 4. At this point it is necessary to provide means for supporting the roof tubes and passing them through the side wall. This is accomplished by supporting the upper part of the wall 26¹ on a horizontal girder-like member formed as shown in full lines in Fig. 13 and which member is built into the furnace wall as shown in Fig. 12.

The girder is made up of a broad, flat top plate 22 which is welded to an outside channel section 24 and an inside I-beam section 25, these members being pierced at 24¹ and 25¹ for the passage of the tubes. A lower plate 23 welded to these members completes the structure, which when in use is positioned in the wall as shown in Fig. 12. From this latter figure it will be seen that the inner edges of the top and bottom plates of the girder reach within about 2 to 3 inches of the inner face of the wall, the open space 28 being filled in with plastic furnace cement as soon as the radiant heat tubes 21 are put in place. Referring to Fig. 13, it will be seen that the end 22¹ of the girder projects outward to a distance approxi-

mately equivalent to one-half the thickness of the member 17 of Fig. 4. With the horizontal girder in position in the wall this flange-like projection of the plate 22 rests on top of member 17 as shown in Fig. 12 and also in Fig. 4 and is welded thereto. By studying the figures it will be seen how the upper section 26¹ of the wall is supported on the girder which in turn rests on the lower wall section 26 and partly on the member 17 by means of the flanged extension 22¹, all of the parts being thus firmly bound together, while the openings in the girder and in member 17 provide for support of the roof tubes.

A similar type of vertically placed girder member formed with both plates 22 and 23 of Fig. 13 arranged with overhanging edges 22¹ and 23¹ is used in connection with the auxiliary buckstays 20 to 20¹¹ in building up the side walls of the still, one such girder being placed in front of each buckstay, the sides of the buckstays being embraced between the overhanging flanges of the two plates as shown in dotted outlines in Fig. 13 which arrangement prevents lateral displacement of the short girder sections from in front of the buckstays. These girders embedded in the wall in front of each auxiliary buckstay provide the upright supports for the depending radiant tube sections which are of course spaced on 20 to 24 inch centers. The open spaces 26² (see Fig. 4) between these buckstays is filled with brick-work, thus completing the furnace wall. Observation peepholes can be arranged in these brick-work sections as desired.

The manner in which the radiant heat tubes are connected together can be traced by the lines joining the tubes, as shown in Figs. 4. It will be noted that certain sections, notably 29, 29¹, 29², 29³ are joined together by lengthened junction box sections provided with clean-out plugs on the sides as well as in front, as is visible in Fig. 4. The central tube rows 20⁵ and 20⁶ are in this figure shown as double rows contained in a single support, but in practice they should be separated from each other the usual distance 20 to 24 inches in order to take advantage of the radiant heat impingement on both sides of single row tubes. 10 and 11 are the final outlets leading from the radiant heat section of the still, while 35 and 35¹ are the inlets thereto.

Referring again to the vertical tube supports, the constructional details of which are shown partly in full and partly in dotted outline in Fig. 13, 22 is one of the girder side plates which has a projecting flange end 22¹, and 23 is the other girder side plate likewise formed with a flange extension 23¹. The buckstay 20 is embraced between these two flanges and rest against the outer surface of the co-operating channel member 24, which latter is flush with the outer surface 26⁴ of the still wall 26. The I-beam 25 forms the inner surface of the girder, and the open channel-like space left in front of it, when the girder is in position in the wall, is intended to be filled in with plastic furnace cement, up to and flush with the inner wall surface 26³ of the furnace, it being understood that the radiant heat tubes are first put in position before filling up this channel.

In the type of tube still illustrated the lower radiant heat tubes are sometimes exposed to great extremes of temperature and it may be advisable in some cases to protect these tubes from danger of injury by enclosing them in metallic casings or sheaths. A type of metallic sheath suitable for this purpose is shown in Figs. 75

6 and 7, and consists of a metallic tube, preferably of a heat-resistant chrome nickel steel alloy, whose internal diameter is slightly less than the external diameter of the tube to be protected. 5 The alloy tube is slit throughout its length as shown in Fig. 6 and is forced over the outside of the furnace tube, the slot permitting sufficient expansion of the alloy tube for this purpose. The furnace tube is thus tightly gripped by its protective sheath, as shown in Fig. 7, the only part remaining uncovered being the narrow slot whose width at no time should exceed $\frac{1}{8}$ ". If the unitary structure described above be dipped into a molten metal, such as tin, brass, bronze, aluminum, etc., the molten metal will be drawn into the capillary spaces between the two tubes and will be retained therein by capillary forces as occurs in standard dip brazing. This provides an all metal contact between the tubes to aid the 10 heat transfer therein. The metal so retained will when heated be perhaps in liquid form, but it will not drain out no matter what be the temperature to which it is exposed.

Fig. 8 shows a case wherein two protective 25 sheaths, one over the other are employed to guard the furnace tube. Any number of sheaths desired may be so used, and it is self evident that replacements can easily and quickly be made whenever necessary by forcing open the slot and 30 withdrawing the inner tube as required.

With cracking stills in order to secure the best returns from any unit, it is important that the initial process of heating the oil to the temperature desired, under the pressure prevailing in the 35 system, be given careful consideration. The illustrations shown in Figs. 17 and 18 show two distinct arrangements of tube stills, embracing the features of this invention, as arranged for high temperature and pressure. The difference in design of the two is intended to show the versatility 40 of the arrangement.

Fig. 17 is a two-zone box type of radiant heat still, having a small convection bank of steel tubes located behind a curtain wall 12. This 45 convection bank is usually arranged 5 tubes wide and 10 tubes high, as explained, in connection with Figs. 1, 2, and 3. It is also provided with an air preheater located below the convection bank for preheating the secondary air for combustion 50 as in the previous designs. Directly over the furnace a series of rows of radiant heat tubes are arranged in widely spaced relation in accordance with the basic features of this invention. Usually these tubes run in a direction at 55 right angles to the tubes of the convection bank, although this particular arrangement is not an absolute necessity, as under certain circumstances they may run in the same direction. The first arrangement however, is to be preferred because the open spaces between the tube rows provide 60 a series of open tunnels into which the combustion gases rise and flow without obstruction over the bridge walls into the convection bank of tubes. The conditions for radiant heat transfer 65 from these incandescent gases to the tubes forming these tunnels is extremely favorable and very intensive cooling of such gases will result from the arrangement. Directly above these widely spaced tube rows, there is a series of horizontally placed rows of tubes, five such rows altogether, being shown in this figure. It will be noticed 70 that the upper three rows shown, are of somewhat larger diameter than the first two lower rows, and that the upper rows of tubes in this 75 section are partially shielded from the furnace

by the lower two rows, all of the tubes in this section being staggered and their center-to-center relationship determined definitely to lessen the heat absorption of the upper rows. This provides for holding the oil in the tube stills for an appreciable period of time depending on the flow rate, without materially absorbing more heat. This is a most important feature in tube still construction as it permits of introducing the time element into oil cracking without resorting to the use of heavy expensive expansion chambers for this purpose such as are commonly employed with most high pressure oil cracking processes. The digestion period of the cracking operation is thus completed in the still itself, all 10 that is required to complete the operation being to flash the cracked stock into an expansion chamber, at substantially atmospheric pressure. By cooling the oil at the instant of flashing, substantially no heavy tar or coke will be precipitated, but a saleable residual fuel oil will result; while if this cooling be omitted, the distillation will be so complete, that practically only residual coke of small amount will be left in the flash 15 chamber.

In such a system the pressure control valve for the process will be located between the still and the low pressure flash chamber, so that by manipulating this valve any amount of pressure from normal atmospheric up can be put on the 20 cracking still as required. In this way it is possible to operate such a process either as a low pressure vapor phase method, or as a high pressure liquid phase oil cracking process; all gradations between the two being available by variation in operating pressure, oil flow and furnace 25 temperatures. The flexibility of such a method is very great indeed as it permits a refiner to adapt his product to market requirements and to change the character thereof at any time it 30 may be necessary to do so.

In the type of still shown in Fig. 17, the bridge wall 12, is provided on its front face with a series of radiant heat tubes 30, set in recesses 30¹ in the front of the bridge wall as in Fig. 3. These 45 tubes are connected into the oil circuit in such manner that the oil after passing through the convection bank of tubes enters this radiant heat section at the bottom by way of transfer lines 31 (where two convection banks are employed as in 50 Fig. 3).

After flowing through these tubes the oil passes by transfer lines 31¹ to the radiant heat section in the upper part of the furnace chamber. The broken line of tubes in Fig. 17 shows the direction of flow in the two oil circuits, which direction is mainly upward to the outlets 10 and 11. The other details are similar to the one described in connection with Fig. 3, and will not be referred 60 to further here.

In Fig. 18 there is shown an application of these principles to an all radiant heat circular still of the De Florez type. This form of still comprises a vertical cylindrical shell with tubes arranged in a circle against the inner wall. In the still illustrated there are provided four such rows; the two outermost rows forming the digestion time element being constituted of tubes of larger diameter than the radiant heat section. The radiant heat section is provided with inwardly projecting widely spaced rows of tubes, the fundamental plane of the tube axes in each row is, in this still, arranged perpendicular to the fundamental surface of the furnace wall. The rows thus present a ribbed-like form to the 75

furnace center wherein combustion takes place by means of burner 32. Care must be taken to design the furnace of sufficient diameter to prevent direct impingement of flame on any of these tube rows, a matter not difficult of accomplishment with upshot furnaces of this type. 33 and 33¹ are the inlets to the two oil circuits, since this still is herein designed as a double circuit type. 34 and 34¹ are the outlets from the still; all of these openings are located either above or below the furnace chamber as may be most convenient and they may be given any form most suitable for the purpose in hand. The direction of oil flow in the circuits is easily traceable from the lines of the figure, and it will be noted therefrom that this flow is mainly outwards toward an increasing diameter so that the oil in passing through the larger tubes of the two outer rows is given sufficient time to complete the cracking reaction without danger of overheating as these larger tubes are shielded more or less from the radiant heat by the smaller sized inner rows. The advantages of the arrangement are self evident as it provides for intensive cracking and digestion of the oil in a single unit, as in the design just previously discussed.

In Figs. 15 and 16 are shown polar diagrams which give a clear idea of the intensity of heat absorption at different points of a radiant heat tube located in a front tube bank directly exposed to an open flame or other source of radiant heat. Fig. 15 shows the absorption by a tube exposed on one side only, while Fig. 16 shows the absorption when the tube has both sides exposed. It will be noted that time element digestion tubes are arranged in rising tiers in the furnace roof on the box type still or adjacent the wall surface of the circular De Florez type in such manner that the oil first flows through the tube rows nearest the radiant heat source and then progressively through the rows further and further away from this source, which arrangement, of course provides diminishing heat absorption for the final passes of the oil stream, in order to avoid overcracking.

The above completes the description of this process wherein an effort at increased efficiency is attempted in oil cracking processes. Stills such as those outlined herein are suitable for any standard type of oil cracking process, such as the tube and tank, the Holmes-Manley, the Dubbs, the Cross, and many other processes wherein it is required to rapidly heat oils to high temperatures with high thermal efficiency. This principle of construction therefore is particularly profitable for high pressure, high temperature oil cracking furnaces, in that the use of radiant heat to secure the reduction of the heating surface of the furnace is of the utmost necessity and importance.

Having thus described my invention, what I claim and desire to obtain by United States Letters Patent is:

1. An oil heater comprising a combustion chamber, a source of heat for the combustion chamber, a heating chamber having a flue gas exit, an air-cooled vertical bridge wall separating the combustion chamber from the heating chamber, a convection heated bank of economizer tubes located in said heating chamber and extending transversely to the general direction of flow of the heating gases in the heating chamber, a series of horizontally disposed rows of radiant heat tubes in the upper part of the combustion chamber adjacent the roof thereof, said rows having

portions in the form of widely spaced depending loops hanging in the free space substantially entirely above the bridge wall and in the combustion chamber above the source of heat and freely exposed thereto in heat transferring relation and 5 heated preponderantly by radiant heat, means for supporting the radiant heat tubes in the still walls and in the free space of the still, means for joining the radiant heat tubes together in series, means for joining the economizer bank of 10 tubes together in series, and means for connecting the economizer bank of tubes in series to the radiant heat tubes in such manner that the oil flow therein is first through the economizer bank of tubes and then through the radiant 15 heat rows to the outlet of the still.

2. A dual circuit oil still comprising a central combustion chamber, a source of heat for the combustion chamber, two separate heating chambers located one on each side of the combustion 20 chamber opposite the other, air-cooled bridge walls separating the combustion chamber from the heating chambers, a convection heated bank of economizer tubes located in each heating chamber and extending transversely to the general direction of flow of the heating gases in the heating chambers, dual oil circuits in the form of a series of horizontally disposed rows of radiant heat tubes in the upper part of the combustion chamber adjacent the roof thereof, 30 said rows having portions in the form of widely spaced depending loops hanging in the free space of the upper part of the combustion chamber above the source of heat and freely exposed thereto in heat transferring relation and heated pre- 35 ponderantly by radiant heat, means for supporting the radiant heat tubes in the still walls and in the free space of the still, means for joining the radiant heat tubes together in series, means for joining the economizer bank of tubes 40 together in series, and means for connecting the economizer bank of tubes in series to the radiant heat tubes in such manner that the oil flow therein is first through the economizer bank of tubes and then through the radiant heat rows to the 45 outlet of the still.

3. A dual circuit oil still comprising a central combustion chamber, a source of heat for the combustion chamber, two separate heating chambers located on opposite sides of the combustion 50 chamber, air-cooled bridge walls separating the combustion chamber from the heating chambers, a convection heated bank of economizer tubes located in each heating chamber and extending transversely to the general direction of flow of the heating gases in the heating chambers, two separate radiant heat banks of tubes, each bank consisting of a series of horizontal tubes located in recesses in the front face of a bridge wall facing the combustion chamber and fully exposed to radiation from the heat source therein, 55 dual oil-circuits in the form of a series of horizontally disposed rows of radiant heat tubes in the upper part of the combustion chamber adjacent the roof thereof, said rows having portions in the form of widely spaced depending loops hanging in the free space of the upper part of the combustion chamber above the source of heat and freely exposed thereto in heat transferring relation and heated preponderantly by radiant 60 heat, means for supporting the radiant heat tubes in the still walls and in the free space of the still, means for joining the radiant heat tubes in the upper part of the still together in series in such manner as to form two separate circuits, 65 70 75

means for joining together the radiant heat tubes located in front of the bridge walls to form two separate circuits, means for joining each economizer bank of tubes together in series, means for connecting the upper end of each economizer bank of tubes to the lower end of one of the radiant heat circuits located in front of a bridge wall, and means for connecting the upper ends of these bridge wall radiant heat circuits to the 5 radiant heat circuits located in the upper part of the combustion chamber in such manner that the oil flow is first upward through the economizer bank of tubes then to the bottom of the bridge wall circuits and upward therein and 10 thence through the radiant heat circuits in the upper part of the combustion chamber to the outlet of the still.

4. Radiant heat stills in accordance with claim 1 as characterized by having a two-pass double 20 bank air preheater provided with horizontal heat interchanging tubes located in the exit flue gas passage of the still below the economizer bank of tubes, means connecting the air-space of the ventilated bridge wall to said air preheater so 25 that air drawn into the upper part of this space will pass through the upper bank of preheater tubes into a transfer space of the air-heater and thence through the lower bank of tubes belonging thereto into a lower separated part of the 30 bridge-wall air-space, passing transversely to the flow of heating gases over the outside of the interchanger tubes of the preheater, the air delivered into the lower air-space of the bridge wall passing thence to a lower horizontal 35 distributing channel in the still floor from which it escapes into the combustion chamber adjacent the heating burners located in the furnace side walls.

5. A radiant heat still comprising a central 40 combustion chamber, a source of heat therefor, a heating chamber, a wall interposed therebetween, a convection heated bank of economizer tubes located in said heating chamber and extending across the general direction of flow of 45 the heating gases thru said chamber, dual oil circuits in the form of a series of horizontally disposed rows of radiant heat tubes in the combustion chamber adjacent the roof thereof, said rows having portions thereof in the form of widely 50 spaced loops depending in the free space of the upper portion of the combustion chamber above its said source of heat and freely exposed thereto in heat transferring relation therewith and heated preponderantly by radiant heat, and 55 means for connecting the economizer bank of tubes in series with the radiant heat tubes in such a manner that the oil flow is first through the economizer bank and thence through the radiant heat tubes to the still outlet.

6. In a furnace for heating hydrocarbon fluids 60 to cracking temperature, a heating chamber divided into radiant and convection heating chambers by a vertical bridge wall, means for producing hot products of combustion for passage 65 through the radiant and convection heating chambers in the order named, interconnected heat absorbing tubes in each heating chamber for conducting a hydrocarbon fluid therethrough, at least a portion of the tubes in the radiant 70 heating chamber being disposed above the bridge wall and arranged in a plurality of interconnected spaced parallel banks of several tubes each disposed in vertical planes parallel to the flow of hot products of combustion toward the convection section to expose the tubes thereof to radiant 75

heat on both sides from the hot products of combustion and the tubes in the convection heating chamber by convection heat therefrom.

7. In a furnace for heating hydrocarbon fluids 5 to cracking temperature, a heating chamber divided into radiant and convection heating chambers by a vertical bridge wall, means for producing hot products of combustion for said furnace, a plurality of interconnected parallel banks of radiant heat absorbing tubes for conveying hydrocarbon fluid being heated from one bank to another disposed above the bridge wall and depending from the roof of the radiant heating chamber in vertical planes parallel to the flow of hot products of combustion toward the convection 10 section and spaced apart to expose the tubes thereof to radiant heat on both sides from the hot products of combustion and heat absorbing tubes in the convection heating chamber for receiving heat from said combustion products pre- 15 ponderantly by convection.

8. In a furnace for heating hydrocarbon fluids 20 to cracking temperature, a heating chamber divided into radiant and convection heating chambers by a vertical bridge wall, means for producing hot products of combustion for said furnace, a plurality of interconnected parallel banks of radiant heat absorbing tubes for conveying hydrocarbon fluid being heated from one bank to another disposed above the bridge wall and depending from the roof of the radiant heating chamber in vertical planes parallel to the flow of hot products of combustion toward the convection 25 section and spaced apart to expose the tubes thereof to radiant heat on both sides from the hot products of combustion, other radiant heating tubes disposed immediately adjacent the walls of the radiant heating chamber and heat absorbing tubes in the convection heating chamber for receiving heat from said combustion products pre- 30 ponderantly by convection.

9. In the art of heating petroleum oil to an elevated or cracking temperature while passing in a stream of restricted cross-sectional area in 40 a radiant heating zone, the improvement which comprises flowing petroleum oil through a tubular conduit composed of series of widely spaced parallel rows of several depending tubes while subjecting the exterior of such tubes to radiant heat from an adjacent zone of combustion to heat said 45 tubes preponderantly by radiant heat, the planes in which the different series of tubes are disposed being spaced sufficiently from each other to insure that sub-divided masses of radiant heat from said combustion zone passing between such 50 planes of tubes will approximate from 20 to 24 inches in thickness and thereby insure a maximum radiative capacity to heat the oil to the desired elevated temperature.

10. In a furnace for heating hydrocarbon fluids 60 to a cracking temperature, a radiant heating chamber, means for producing hot products of combustion for heating said chamber, a plurality of heat absorbing tubes in said chamber, means for interconnecting said tubes to form a plurality 65 of separate heating coils, each of which is adapted to convey a separate stream of hydrocarbon fluid therethrough, at least a portion of the tubes of each heating coil being arranged in a plurality of spaced parallel banks of several tubes each 70 disposed in vertical planes adapted to be heated preponderantly by radiant heat from hot products of combustion to expose the tubes of each bank to intense radiant heat on both sides therefrom for substantially their entire length to heat 75

the hydrocarbon fluid passing through each heating coil to an elevated temperature.

11. In a furnace for heating hydrocarbon fluids to a cracking temperature, a radiant heating chamber, means for producing hot products of combustion for heating said chamber, a plurality of heat absorbing tubes in said chamber, means for interconnecting said tubes to form a plurality of separate heating coils, each of which is adapted to convey a separate stream of hydrocarbon fluid therethrough, at least a portion of the tubes of each heating coil being arranged in a plurality of spaced parallel banks of several tubes each disposed in vertical planes adapted to be heated predominantly by radiant heat from hot products of combustion to expose the tubes of each bank to intense radiant heat on both sides therefrom for substantially their entire length to heat the hydrocarbon fluid passing through each heating coil to an elevated temperature, a convection heating chamber receiving combustion products from said radiant heating chamber, heat absorbing tubes in said convection heating chamber for conveying hydrocarbon fluid to be heated and means for connecting tubes in said convection heating chamber to at least one of the heating coils in said radiant heating chamber.

12. In a furnace for heating hydrocarbon fluids to cracking temperature, a radiant heating chamber, means for producing hot products of combustion for heating said chamber, a vertical bridge wall over which the exit furnace gases flow, a plurality of heat absorbing tubes in said chamber, a portion of said tubes being disposed alongside of the walls of the radiant heating chamber and heated predominantly by radiant heat, another portion of said tubes being disposed above said bridge wall and arranged in a plurality of spaced parallel banks of several tubes each disposed in vertical planes parallel to the flow of hot products of combustion toward the bridge wall to expose the tubes of each bank to intense radiant heat on both sides from the hot products of combustion and means for connecting the portions of tubes to each other for conveying a stream of hydrocarbon fluid therethrough.

13. In a furnace for heating hydrocarbon fluids to cracking temperature, a radiant heating chamber, means for producing hot products of combustion for heating said chamber, a vertical bridge wall over which the exit furnace gases flow, a plurality of heat absorbing tubes in said chamber, a portion of said tubes being disposed alongside of the walls of the radiant heating chamber and heated predominantly by radiant heat, another portion of said tubes being arranged above said first mentioned portion and above said bridge wall disposed alongside of the walls of the radiant heating chamber and in a plurality of spaced parallel banks of several tubes each disposed in vertical planes parallel to the flow of hot products of combustion toward the bridge wall to expose the tubes of each bank to intense radiant

heat on both sides from the hot products of combustion and means for connecting the portions of tubes to each other for conveying a stream of hydrocarbon fluid therethrough.

14. In a furnace for heating hydrocarbon fluids to a cracking temperature, a radiant heating chamber, means for producing hot products of combustion for heating said chamber, interconnected heat absorbing tubes in said chamber for conducting a continuous stream of hydrocarbon fluid therethrough, said tubes being arranged in a plurality of spaced parallel banks of several tubes each disposed in vertical planes adapted to be heated predominantly by radiant heat to expose the tubes of each bank to intense radiant heat on both sides therefrom for substantially their entire length to heat the fluid passing therethrough to an elevated temperature and means for protecting the tubes of the parallel rows nearest the means for producing hot products of combustion from excessive heat.

15. In a furnace for heating hydrocarbon fluids to cracking temperature, a combustion chamber, means for producing hot products of combustion for said combustion chamber, a plurality of heating chambers separated from said combustion chamber by bridge walls in communication with said combustion chamber for receiving products of combustion therefrom, heat absorbing tubes in said combustion chamber disposed above said bridge walls, at least a portion of the tubes being arranged in a plurality of spaced interconnected parallel banks of several tubes each for conveying hydrocarbon fluid from one bank to another disposed in vertical planes parallel to the flow of hot products of combustion toward the heating chambers to expose said tubes to radiant heat on both sides from the hot products of combustion, and heat absorbing tubes in each heating chamber for receiving heat from said combustion products by convection.

16. In a furnace for heating hydrocarbon fluids to cracking temperature, a radiant heating chamber, means for producing hot products of combustion in the lower part of said radiant heating chamber, means forming a passage for withdrawing the products of combustion from the radiant heating chamber, a plurality of interconnected parallel rows of radiant heat absorbing tubes in the upper part of the combustion chamber for conveying hydrocarbon fluid being heated from one row to another, said rows having portions of several tubes each substantially entirely above the lower part of said radiant heating chamber wherein the hot products of combustion are generated and depending in a plurality of spaced parallel vertical planes parallel to the flow of hot products of combustion towards said passage in the combustion chamber and spaced apart to expose the tubes thereof to radiant heat on both sides from the hot products of combustion after generation thereof.

DONALD L. THOMAS.

CERTIFICATE OF CORRECTION.

Patent No. 2,072,535.

March 2, 1937.

DONALD L. THOMAS.

It is hereby certified that error appears in the printed specification of the above numbered patent requiring correction as follows: Page 9, second column, line 27, claim 15, before the word "bridge" insert the word vertical; and that the said Letters Patent should be read with this correction therein that the same may conform to the record of the case in the Patent Office.

Signed and sealed this 11th day of May, A. D. 1937.
